UNITED STATES PATENT OFFICE.

ALFRED BRIDGES, OF NEWTON, MASSACHUSETTS.

IMPROVED MODE OF CONNECTING CARS TO TRUCKS.

Specification forming part of Letters Patent No. 44 278, dated September 20, 1864.

To all whom it may concern:

Be it known that I, ALFRED BRIDGES, of Newton, in the county of Middlesex and State of Massachusetts, have invented certain new and useful Improvements in the Means of Connecting Cars to Trucks; and I do hereby declare that the following is a full and exact description thereof.

The accompanying drawings form a part of this specification.

Figure 1 is a side view of a truck and of a portion of a car-body constructed and connected according to my invention. Fig. 2 is a section through the center of one of the springs and its connections. Fig. 3 is a section through one of the caps employed, showing the preferable mode of construction.

Similar letters of reference indicate like parts in all the figures.

My present invention is an improvement on that shown in the patent issued to me dated the 2d of June, 1863. In both the car-body is suspended from the truck by a spring or yielding connection. My present invention is an improvement, in that it involves a superior arrangement of the principal springs, sustains them by auxiliary springs, and provides for reducing their abrasion so as to allow them to perform in the novel manner required without impairing their durability.

To enable others skilled in the art to make and use my invention, I will proceed to describe its construction and operation by the aid of the drawings and of the letters of reference marked thereon.

A are the wheels; B, the axles, and C the axle-boxes. These parts, as also the car-body M, are made in the usual manner.

D is the truck-framing, formed of wrought-iron, so as to be light, strong, and elastic. The cross-bars E may be extended across and form the only necessary connection between the two sides of the truck-frame. A strong lug or shelf, d, is produced on the truck-frame D at the points represented, adapted to support the rubber springs H. The lug d has a large hole in its center, the use of which will presently appear. Brakes, safety-chains, and other devices necessarily or commonly used on trucks may be attached in any approved manner not represented.

F are strong inverted pedestals bolted on the car-body and extending down so as to pre-

sent their lower ends under the springs H H. A bolt, G, of wrought-iron or steel, suspends the weight of the car-body by these pedestals in the manner now to be shown. The rubber springs H are cylindrical, and provided with a cylindrical hole, which is considerably larger than the slender bolt G. A thimble, h, cast on the covering-plate J, extends about one-third of the depth of each spring H. The remaining two-thirds of the depth of the spring H is not lined in any manner, but is left with the full size of the hole empty, so as to allow the bolt G to swing freely in all directions. The hole in the iron support d is also of sufficient size to allow freedom for such motion as before intimated.

N N are stout springs of steel in plates, or of any other suitable material, bolted to the truck-frame D at the points O and P, as indicated, and presenting their thinner ends directly over the covering-plates J and springs H. The bolts G are extended up through the springs N and secured by a convex nut, which allows the bolt G, with its dependent load, to swing in all directions. The weight of the car is supported on the lower ends of these bolts G, through the medium of the hanging pedestals F and convex heads g on the bolts G. These parts are also adapted to allow a swinging of the car-body in all directions by reason of the convex heads g and of the tapering form of the hole in the pedestal F, as represented. The auxiliary springs N tend by their elasticity to stand considerably above the top of the rubber springs H; but the weight of the car bends them down, so that they touch the top of the covering-plates J at all ordinary times. With each jolting movement of the truck in traversing over irregularities in the track the spring N contributes its elastic force to aid the spring H in properly and gently resisting the motion and transmitting only a gentle, undulating movement to the car-body. With each of the slight sidewise movements of the truck-frame D, due to constantly-recurring causes, the bolts G swing or move horizontally at their upper ends in the required directions, while the pedestal or bracket F, and consequently the car-body, moves very slightly, if at all.

In case the car-body, in obedience to an impulse received from the movement of the truck, as just described, or from any other cause, seeks to move sidewise, or forward, or back-

ward while the truck remains relatively at rest, my invention allows it to do so, but in a peculiar manner. It allows it to swing with perfect freedom a very little; but if the movement becomes considerable the motion is resisted, and the car-body is brought back forcibly by the action of the same springs H as aid to support the load. This follows from the form and arrangement of the parts, because the suspension-bolt G fits loosely in the cap J and thimble h while hanging vertically and while swinging in very small arcs; but so soon as the pendulous motion reaches a certain limit the bolt G compels the thimble h and cap J to turn with it, and this turning compels a change in form of the rubber mass H, which is vigorously resisted by its elastic force. The leaf-springs N not only increase the strength and elasticity of the support for the car, but by their arrangement relatively to the rubber springs H and to the truck-frame D d tend to relieve the latter from strain. If the entire weight were carried, as in my former arrangement, on the overhanging ends of the truck-frame, the tendency would be to depress the ends and elevate the center portion of the truck-frame. This would be the case with my present construction if the springs N were dispensed with and the whole weight thrown upon the truck-frame through the shelves d d, which form in effect overhanging ends of the truck-frame, because they are beyond the axles. The effect would be to bend the part D into a more or less curved arch; but my springs N take a portion of the strain and transfer it to the central, or near the central, portion of the framing, inducing a severe pressure downward at the points O and a lifting force at the points P. The framing is sufficiently trussed to resist the upward strain on this short length between the points O O; but if it were not it could be avoided by slightly adding to the weight of the two springs N N, and extending the material thereof along the center, so as to join the two into one strong single spring. It will of course be understood that the boxes C, which I have said are of the usual construction, may be allowed to slide up and down in the jaws in the frame of the truck, and may be each provided with independent springs in the well-known manner, if preferred. I have, however, represented them as fixed in the framing, and believe that a very simple form of box adapted to carry the lubricating material, but not to move in the jaws, will serve very satisfactorily in connection with my invention.

I may add that my invention is capable of being used in part with good effect even without the other parts here represented. Thus my principal springs H may be used with some advantage to carry the load, and allow it to swing in the manner shown, by passing the bolts G, with a little play, through the plates J without the thimbles h; but I believe the thimble h to be of great service in

connection with the other parts, both because it gives a longer hold for the bolt G in arresting a too violent swinging motion, and because it keeps the load accurately on the center of the spring H, and allows a spring with a large cylindrical hole to be used—such as are made for other uses—instead of requiring springs to be made for the especial purpose with conical holes. They also serve usefully by receiving the friction due to the working of the bolt G, which might otherwise wear away and destroy the interior of the hole in the rubber H or in the covering-plate J, or in both. The spring H need not be always of rubber, as any allied material or compounds of gums or other elastic material, in a form corresponding with that here represented, may be employed in the same manner. Steel may also be used as a material therefor by properly arranging coils or series of layers of steel, properly tempered and adapted to allow both the vertical and swinging motions. I prefer rubber for many reasons, but do not confine myself thereto.

Some of the advantages due to certain features of my invention may be separately enumerated, as follows:

First. By reason of the fact that my rubber springs H are carried upon the truck, and the weight of the car is suspended directly therefrom, in the manner shown, I am able to simplify the mechanism and reduce its cost and weight, and can allow the car to swing smoothly and noiselessly and yet be partially restrained by the spring, so as to limit the extent of the vibrations.

Second. By reason of the fact that my spring N acts in connection with my spring H, and that both are secured to the truck-frame D d at the points shown, I am able to relieve the truck from much of the strain which tends to distort it, and to distribute the load very uniformly and desirably. I am also able by this means to so far relieve the springs H as to allow them to act more freely to allow and gently restrain lateral and forward and rearward movements.

Third. By reason of the fact that my thimble h extends downward within the upper portion of the spring H, in the manner shown, I am able, by making it rigid upon the plate J, to secure a longer bearing to resist the side strains upon the bolt or suspension-bar G, and, whether the thimble be rigid or loose, I am able to use ordinary rubber springs, with the ordinary cylindrical holes through them, and obtain all the liberty desired at the bottom of the hole, as also to effectually resist most of the friction due to the working of the bolt G.

Having now fully described my invention, what I claim as new therein, and desire to secure by Letters Patent, is as follows:

1. In railroad-cars, the spring H on the truck-frame, so combined and arranged with the suspension-rod G or its equivalent that it

controls both vertical and side motions, substantially as herein set forth.

2. The combination of the two springs H and N with the truck-frame D *d*, substantially in the manner and for the purposes herein specified.

3. The thimble *h*, when used with the spring

H, truck-frame D *d*, suspension-rod G, and pedestal F, substantially in the manner and for the purposes herein specified.

ALFRED BRIDGES.
